INVENTOR
Gabol Peterson,
BY *Mme. Lee.*
ATTORNEY

UNITED STATES PATENT OFFICE.

GABULL PETERSON, OF TARPON SPRINGS, FLORIDA.

PROPELLER GUARD.

Application filed July 5, 1928. Serial No. 290,431.

This invention relates to propeller guards.

An object of the invention is the provision of a guard for a propeller for those types of boats which are used for diving purposes and in which it is necessary to prevent fouling the life line and hose connected with the diver's outfit, the guard being in the form of a cage which is readily removable from its guarding position when desired.

A further object of the invention is the provision of a guard for a propeller which is in the form of a pair of cages adapted to be removably secured in position at the opposite sides of the keel extension of the boat with the cages being secured to a rod which is slidably mounted in guides adjacent the usual rudder.

This invention will be best understood from a consideration of the following detailed description, in connection with the accompanying drawings; nevertheless, it is to be understood that the invention is not confined to the disclosure being susceptible of such changes and modifications as shall define no material departure from the salient features of the invention as expressed in the appended claims.

In the drawings:

Figure 1 is a side view in elevation of a guard constructed according to the principles of my invention and applied to the keel extension of a boat.

Figure 2 is an end view of the same,

Figure 3 is a vertical section taken along the line 3-3 of Fig. 1,

Figure 4 is a horizontal section taken along the line 4-4 of Fig. 3,

Figure 5 is a vertical section taken along the line 5-5 of Fig. 1.

Referring more particularly to the drawings, 10 designates the hull of a boat of the type used for diving purposes and in the sponge fishing fleets. The stern of the boat 45 is provided with a keel extension 11 which extends centrally and vertically of the boat. The keel extension has an opening 12 to accommodate the propeller 13. A rudder 14 is mounted on the keel extension and may 50 be controlled by a tiller 15. The present invention provides a guard in the shape of a basket located upon each side of the opening 12 whereby the propeller 13 is completely encased and will prevent the usual life line and hose coming in contact therewith. Each propeller guard consists of a

rod 20, a rod 21, which is bent to conform to the contour of the basket or protecting device, and horizontally disposed bars 22 which have one of their ends secured to the rod 20, and their other ends to the rod 21. A transverse bar 23 is secured at its upper ends to portions of the rod 21 and also the bars 22. The bars 22 are bent intermediate their ends in order to properly space the guard 65 from the propeller blades.

A pair of guides 30 are secured to the keel extension 11 and in parallel relation with the rod 20 and receive the edges of a plate 31 which is slidably mounted in the guides. Bearings 32 project from the plate 31 in spaced relation and are provided with passages 33 to receive the rod 20. These bearings are split and are provided with a cap 34 which is bolted at 35 to the bearings 32. By this construction it will be seen that the rod 20 will be removed from the plate 31, as desired.

The guides 30, as shown more particularly in Fig. 4, are of angle iron construction and consist of a flange 40 having a right angular portion 41 from which projects a flange 42 at right angles to the portion 41 which is spaced from the keel 11 to receive the edges 43 of the plate 31.

The lower end of the rod 20 is located within a socket 45 which is secured to the keel extension 11. A collar 46 is secured to the rod 20 above the upper bearing 32, while the collar 47 is secured to the rod 20 below 90 the lower bearing 32. These collars maintain the rod 20 in position on the plate 31, while permitting the plate to be moved in its guides in a vertical position.

A plurality of cleats 50, 51 and 52 are 95 secured in spaced relation, as shown at 53, to the keel extension of the boat and are provided with an offset flange 54 providing a socket 55 to receive portions of the rod 21 which forms the periphery of each guard, 100 so that when the guard is in position, these cleats will aid in maintaining the guard in operative relation with the propeller 13.

A handle 60 is secured at 61 to the rod 20 and extends inwardly and is received by a 105 support 62 secured to the hull of a boat.

The operation of my device is as follows: When the boat is being propelled from one position to another the guard is elevated by releasing the handle 60 from the support 110 62, whereby the guard may be raised through the medium of the plates 31 and the

guides 30, when placed in a position where it will not interfere with the operation of the propeller and prevent the proper speed of propulsion of the boat. However, when the divers are at work and the boat is moved from one position to another, the guards are let down until the lower portion of the rod 20 is received by the cleats 50 to 52 inclusive, whence it is held in position.

10 I claim:

1. A propeller guard comprising a pair of open work guard members, a rod rigidly connected with each guard member, means for retaining the free end of a guard in protective relation with the propeller, means for slidably mounting the rod whereby reciprocation of the rod will release the guard from the retaining means and move said guard out of operative relation with the propeller.

15 2. A propeller guard comprising a pair of open work guard members, a rod slidably

20 mounted and rigidly connected to a guard member, means for retaining the free end of the guard in protective relation with the propeller, a plate secured to the rod and guides receiving the plate whereby the rod may be reciprocated, and move the guard to an inoperative position and out of protective relation with the propeller.

25 3. In a propeller guard comprising a pair of open work guard members, a rod slidably mounted and rigidly connected to a guard member, means for retaining the free end of the guard in protective relation with the propeller, a plate secured to the rod and guides receiving the plate whereby the rod may be reciprocated, and move the guard to an inoperative position and out of protective relation with the propeller, a socket in line 30 with the rod and adapted to receive one end of the rod when the guard is retained in an operative position.

35 GABULL PETERSON.
